ATTORNEY

UNITED STATES PATENT OFFICE.

ALICE A. ROBERTS, OF BROOKLYN, NEW YORK.

BOTTLE-CLOSURE

1,002,318.

Specification of Letters Patent. Patented Sept. 5, 1911.

Application filed January 29, 1909, Serial No. 474,982. Renewed January 20, 1910. Serial No. 539,139.

To all whom it may concern:

Be it known that I, ALICE A. ROBERTS, a citizen of the United States, and resident of the borough of Brooklyn, in the county of Kings and State of New York, have invented certain new and useful Improvements in Bottle-Closures, of which the following is a specification.

This closure is of the general type designed to properly seal the mouth of milk bottles and analogous receptacles where a firm and air tight closing is desired by a means that does not allow of a continuous, or even a second use.

Much has been done in this general class as is evidenced by patents which have been issued to myself and others, but in the design of this closure I have included means for a complete and satisfactory operation under any, even the most rigid conditions.

It has been found desirable to close a receptacle, particularly a milk bottle, in a manner that was not only quick and therefore economical, but also in a way that is air tight and clean. I have provided for all of this and have in addition, means for covering and inclosing the lip or flange of the bottle, thereby protecting it from the dirt and germs which are collected thereon during much handling and transportation.

I have found efficient means for accomplishing the end sought without adding greatly to the expense of manufacturing nor adding to any great extent, to the cost of applying a closure.

The material which I have adopted is strong and somewhat pliable and readily adapts itself to the shaping which I find necessary.

The following is what I consider the best means of carrying out this invention.

The accompanying drawings form a part of this specification, in which:

Figure 1 is a side elevation of the upper portion of a milk bottle to which my closure has been applied. Fig. 2 is a vertical section corresponding to Fig. 1. Fig. 3 indicates the closure disassembled showing more completely each of the separate members.

Similar letters of reference indicate like parts in all the figures where they appear.

A is the neck of a bottle, it is of the ordinary and long approved construction. An annular lip A¹, at the top forms the mouth

of the bottle, and a shoulder or rabbet A², is 55 within the mouth of the bottle. The sides of the shoulder are nearly perpendicular and the bottom is flat and at right angles to the sides. The depth of the shoulder, or the sizes of the mouth, neck, or flange, may be 60 varied at will.

B indicates the cap, the exterior portion of my closure. It is of one piece and, before being pressed into the shape of a cap, four radial slits are produced which nearly 65 divide the sheet, as it is then, in four segments.

The material, preferably paper, of which this cap is formed is of such a nature, that after it is shaped, by a hot press or otherwise, into the desired form it will maintain its adopted shape almost indefinitely, or at least until some unusual condition shall force it into another more or less regular shape. 75

Two holes are produced in the top of the cap to receive the ends of a wire as will be described later. When the cap is folded or pressed into the desired shape, the parts adjacent to the four slits fold one upon the 80 other and in this position they are glued or pasted to produce a complete closure. In my experiments, I have found that it is better to delay pasting the overlapping portions of the cap until it is in its place over the mouth 85 and about the neck of a bottle.

C is a disk which may be of the same material as the cap but I prefer to use a paper which is more highly sized and therefore more impervious to moisture. In shape this 90 disk C is circular and of a size sufficient to fit closely the open neck of a bottle and capable of being forced into place on the shoulder in the neck, by being arched slightly downward. This disk is similar and performs all of the functions of the ordinary disk of this general type, except that the upper side is slightly corrugated near its periphery to receive and retain a supply of waxy material such as paraffin. Two holes 100 c, c¹ are produced in the center of the disk for a purpose which shall appear later.

A separating piece D serves an important function so I will describe its peculiarities of construction. In plan it is circular, but a 105 side elevation or section reveals that at four places the material has been pressed upward out of a plane to some little extent.

Two holes, a , a^1 are produced in the center to match the corresponding holes c , c^1 in the closing disk C.

A ring for removing my closure is shown at E.

When the parts are constructed according to the foregoing description they are secured together in the following manner, after which they are ready to satisfactorily operate in the mouth of a bottle for which they are designed. A wire F, is bent through the ring E so that its ends extend an equal distance one on each side below the ring. The ends of the wire are then passed through the holes provided for it in the center of the cap B, and in like manner the separating piece D and the disk C are successively placed upon the extending ends of the wire F, after which the ends of the wire are bent sharply at right angles to hold all of the parts firmly together. A wafer G is then secured to the under side of the disk C, by pasting or otherwise in such a manner as to completely cover the ends of the wire F. My closure is now nearly ready for service, the last though important step is to deposit a supply of paraffin on the disk C. I accomplish this by any of the well known means such as submerging the entire cap, or flowing warm paraffin into the cap while it is in an inverted position, or by submerging the disk C into a vessel of just sufficient diameter to allow the disk to enter while excluding the remaining parts.

Modifications may be made within the scope of the appended claims without departing from the principle or sacrificing the advantages of this invention.

40 The overlapping portion of the cap B caused by the slits may be used without pasting if desired.

The slits in the cap may be dispensed with by using a pulpy material which lends itself more readily to the treatment and shaping, 45 such material is known to the arts in the manufacture of electric switches, for the purpose of installation.

The separating piece D may be omitted and a number of thin disks used to accomplish the desired result.

The paraffin used on the lower disk may be omitted, if such is not desired.

The quality of material and the expense of manufacture may be varied within 55 a wide range.

Having described my invention what I claim and desire to secure by Letters Patent is:

1. In a bottle closure, a deep and slitted 60 inclosing cap, a disk having corrugations upon its upper side secured within said cap, a separating piece arranged between said cap and said disk, a securing wire extending through said cap, said disk and said separating piece and means for removing or replacing the whole as specified.

2. In a bottle closure, a deep and slitted 70 inclosing cap, a disk having corrugations upon its upper side secured within said cap, a separating piece arranged between said cap and said disk, a securing wire extending through said cap, said disk and said separating piece, and an operating ring held by 75 said securing wire all combined for joint operation.

Signed at New York city in the county of New York and State of New York this 25th day of January A. D. 1909.

ALICE A. ROBERTS.
